UNITED STATES PATENT OFFICE.

FELIX WOLF, OF NEW YORK, N. Y.

AUTOMATIC RAILROAD-SWITCH.

No. 911,190.

Specification of Letters Patent.

Patented Feb. 2, 1909.

Application filed September 25, 1907. Serial No. 394,558.

To all whom it may concern:

Be it known that I, FELIX WOLF, a citizen of the United States, residing at New York, in the county of New York and State of New York, have invented a new and useful Improvement in Automatic Railroad-Switches, of which the following is a specification.

The present invention pertains to railroad safety devices, and has for its object to over-
come any difficulties, and to eliminate any irregularities which are liable to happen at all switches in use at present, make the setting of the switches more accurate and safe, and avoid accidents, caused by faulty setting of the switch through negligence of the switchman, and to prevent the consequent loss of life by not intrusting the lives of the passengers to the punctuality and attention of one man.

20 In the accompanying drawings forming part of this specification similar reference letters denote corresponding parts.

Figure 1 is a diagrammatic bird's eye view, and Fig. 2 is a diagrammatic side elevation of my invention. Fig. 3 and Fig. 4 represent two views of the part of the invention mounted on the locomotive of the train, and Fig. 5 is a perspective view of an interchangeable plug for the cylindrical cam 30 *k* shown in Fig. 3.

With reference to the drawings *a* denotes the switch, which is movable sidewise, *b* and *b'* are two electromotors, each one being capable of being driven in the opposite direction of the other. The armatures of both motors are rigidly connected by screw *c*, which is held in place by the collar *d*, and the standards *e* and *e'*, but is free to revolve in either direction. The switch is supplied with sleeves *E* and *E'*, bore and threaded out to fit screw *c*. When an electric current is supplied to motor *b*, the screw *c* will be turned in one direction, the armature of the idle motor will be turned along, and the switch will be forced to one side; when motor *b'* is running motor *b* will be idle, the screw *c* will be turned in the opposite direction, the armature of the idle motor *b* will be turned along, and the switch will be forced to the other side.

45 *D* is a device situated between the tracks, a convenient distance ahead of the switch, designed to complete the current of the battery *B*, either through motor *b* or motor *b'* actuating the switch.

f₁, *f₂*, *f₃* and *f₄* are contact strips of metal,

forming the ends of the wires *T₂*, *T₃*, *T₅* and *T₆*, which form together with wires *T₁* and *T₄* two interrupted electric circuits, which may be made to run either through motor *b* or motor *b'* respectively.

G₁ and *G₂* are plates resiliently mounted above contact strips *f₁*, *f₂* and *f₃*, *f₄* respectively, and designed to connect each pair of contact strips, if sufficient pressure is brought upon them.

H and *H₁* are flat springs, to which the one end of plates *G₁* or *G₂* respectively are fastened, and are arranged to reduce the pressure brought upon the plates *G₁* or *G₂*.

In the preferred arrangement shown at *D* Fig. 1, if pressure is brought upon plate *G₁*, the same will connect the contact strips *f₁* and *f₂*, and will complete the current through motor *b*; motor *b* will run and motor *b'* will be inactive; the armature of the inactive motor *b'* will be turned along in the direction motor *b* works, and the switch will be forced to one side. If plate *G₂* is forced downwards, *b'* will be active and *b* will be inactive, and the switch will be forced to the opposite side.

h is a lever resiliently mounted between the tracks, and is designed to engage with the part *i*.

B is a battery furnishing current to either of the motors, when the corresponding plate (either *G₁* or *G₂*) is depressed, and may be conveniently kept at the railroad station.

Fig. 3 is a device mounted in the locomotive or front car of the train, designed to bring pressure either on plate *G₁* or *G₂* of the different switches, which the train is to pass, while the same is in motion, by means of the wheels *m* or *m'*, as previously determined, and setting the different switches according to the route the train has to take.

h is a changeable cam consisting of a cylinder supplied with a double row of holes, arranged in the form of a helix, which are fitted to receive plugs of the form shown in Fig. 5, and also indicated at *A* Fig. 3 and Fig. 4. If a plug is brought into a hole of the left helix, it will come under the short part of lever *l*, and the wheel *m* will be forced downwards, and by passing the contact plates, will run over *H*, bringing pressure on *G₁*, and will complete the current through motor *b*, and the switch which may be a good distance ahead yet will be set. As the plugs of the cam are interchangeable, the same may be arranged to set the switches

90
95
100
105
110

automatically for any route the train is to take.

n is a ratchet wheel, slidably keyed on axle *o*.

5 *p* is a screw running in bearing *r*, with a helix of the same pitch as the one of the cam, and is designed to move the cam in the direction of its own helix, when the ratchet wheel *n* is turned.

10 *i* is a lever fulcrumed at *s* and protruding through the bottom of the locomotive or front car of the train, and is designed to engage with part *h* of Fig. 1 and Fig. 2, as soon as the wheels *m* or *m*₁ have passed the 15 contact plates *G*₁ or *G*₂, respectively.

P is a flat spring which forces lever *i* to its original position after it gets out of contact from lever *h*.

The flat springs *H* and *H*₁, of the contact 20 arrangement *D* are also suitable to insure contact when the cars of the trains carrying the cam-and-lever arrangement are differently loaded, allowing for any differences in the height of the top of the car, when the 25 car springs are more or less compressed.

The lever *i* is hinged to lever *t* which is fulcrumed at *u*.

z is a plug arranged to stop lever *t* as soon as it has moved the ratchet wheel *n* one 30 tooth.

R is a joint of lever *t* supported by a flat spring, to allow the lever point to jump to its former position over the next tooth after the ratchet wheel is turned.

35 When *i* comes in contact with *h*, the lever *t* will be actuated a short distance, and will turn the ratchet wheel *n* one tooth, which will be held in this place by the click *v*. The click *v* is pressed against the ratchet 40 wheel *n* by a flat spring. As the ratchet wheel is slidably keyed to the axle *o*, it will turn the cam *k* to the next plug hole on each helix, and if a plug on one helix is brought into one of these holes under the short part 45 of either lever *l* or *l*₁, the same will be elevated a short distance, which distance will be enlarged by means of the long arms of the levers *l* or *l*₁, and transmitted to either 50 wheel *m* or *m*₁ as the case may be. Those wheels protrude through the bottom of the locomotive or first car of the train.

w and *w*₁ are guides to maintain the direction of the levers *x* and *x*₁ carrying the wheels *m* and *m*₁.

55 *y* and *y*₁ are springs, arranged to force levers *x* or *x*₁ back to their former position, after the plug of the cam is removed from under the short part of the levers *l* and *l*₁, respectively.

60 If, for instance, a train is to pass in the direction indicated by the arrow in Fig. 1, a plug on the cam will be brought under the short part of lever *l*, before the train passes the previous switch, and the wheel *m* will 65 be forced downwards, and in passing the

contact arrangement shown in Fig. 1 and Fig. 2 will depress *G*₁ and actuate motor *b*, which will force the switch to the proper side. As soon as wheel *m* leaves the contact plate *G*₁, lever *i* will engage with *h* of the contact arrangement, the ratchet wheel *n* will be actuated, which will turn cam *k*, a plug of the cam *k* will be brought under the short part of either lever *l* or *l*₁, as the case may be, and the device will be adjusted to 70 properly set the switch following the one which the train is to pass now.

It will be gathered from the foregoing that, in addition to the new and practical advantages ascribed to my novel device, the 80 same works safely, and may be easily adjusted for any route a train is to take, by simply inserting plugs at the proper places in the cam, needs little attention, and will stand any usage that it may safely be subjected to.

I do not wish to restrict myself to the particular construction and arrangement shown, but—

What I claim and desire to secure by Letters Patent is:

90 1. In an electric and automatic railway switch two motors to operate the switch, the armatures of the same being connected to a screw, transversely located between the rails and adapted to directly set and lock the 95 switch.

2. In an electric and automatic railway switch two motors to operate the switch, each motor designed to be driven in the opposite direction of the other, the armatures 100 of the motors being connected to a screw transversely located between the rails and adapted to directly set and lock the switch.

3. In an electric and automatic railway switch two motors to operate the switch, 105 each motor designed to be driven in the opposite direction of the other, the armatures of the motors being connected to a screw, transversely located between the rails, which is adapted to directly set and lock the switch, 110 and a contact arrangement to complete the current.

4. In an electric and automatic railway switch two motors to operate the switch, the armatures of the motors being connected to 115 a screw, transversely located between the rails, which is adapted to directly set and lock the switch, an electric source to furnish current to the motors, and a contact arrangement to complete the current.

5. In an electric and automatic railway switch two motors to operate the switch, the armatures of the motors being connected to a screw, transversely located between the rails, which is adapted to directly set and 125 lock the switch, a contact arrangement to complete the current, and means to operate the contact arrangement automatically.

6. In an electric and automatic railway switch two motors to operate the switch, the 130

- armatures of the motors being connected to a screw, transversely located between the rails, which is adapted to directly set and lock the switch, a contact arrangement to 5 complete the current, means to operate the contact arrangement automatically, and means situated between the rails, suited to actuate a device mounted on the locomotive which operates the contact arrangement.
- 10 7. In an electric and automatic railway switch two motors to operate the switch, a contact arrangement to complete the current, and means to actuate the contact arrangement automatically by means of a cam which 15 is interchangeable.
8. In an electric and automatic railway switch two motors to operate the switch, the armatures of the motors being connected to a screw, transversely located between the 20 rails, which is adapted to directly set and lock the switch, a contact arrangement to complete the current, means to operate the contact arrangement automatically, means situated between the rails and suited to act- 25 tuate an arrangement mounted on the loco-

motive and a cam which is interchangeable, capable of adjusting the device which actuates the contact arrangement.

9. In an electric and automatic railway switch two motors to operate the switch, the 30 armatures of the motors being connected to a screw, transversely located between the rails, which is adapted to directly set and lock the switch, a contact arrangement to complete the current, means to operate the 35 contact arrangement, a device situated between the rails and suited to actuate an arrangement mounted on the locomotive, a cam which is interchangeable, capable of adjusting the device which actuates the contact arrangement, and means to actuate the cam automatically.

In testimony whereof I have hereunto set my hand in presence of two subscribing witnesses.

FELIX WOLF.
